UNITED STATES PATENT OFFICE.

BÉLA BENÖ SCHÄFER, OF BADEN, SWITZERLAND, ASSIGNOR TO GLEICHRICHTER-
AKTIENGESELLSCHAFT, OF GLARUS, SWITZERLAND.

APPARATUS FOR PROTECTING METAL-VAPOR RECTIFIERS.

1,367,098.

Specification of Letters Patent.

Patented Feb. 1, 1921.

Application filed February 10, 1920. Serial No. 357,751.

To all whom it may concern:

Be it known that I, BÉLA BENÖ SCHÄFER, a citizen of the German Realm, residing at No. 39 Schartenstrasse, Baden, Switzerland, have invented certain new and useful Improvements in Apparatus for Protecting Metal-Vapor Rectifiers, of which the following is a specification.

It has already been proposed to construct the arc-guiding tubes, pipes or the like leading from the anodes to the cathode, in such a manner that their mouths are turned away from one another. This arrangement is based on the desire to remove the anode as much as possible from the injurious action of the cathode, which latter may consist for instance of an irradiation with ultra-violet rays, or in the action of the so-called negative flame rising from the cathode, or finally in the impact of mercury globules. In rectifiers comprising a glass vessel and a spherical form of the container, it is comparatively easy to employ such arrangements. It is however much more difficult to do this in the case of metal-vapor rectifiers having a metal vessel, in which the anodes are offset from the axis of the vessel and shifted close to the wall of the vessel.

Nevertheless, in order to attain the desired effect, the round aperture of the arc-guiding sleeve is according to this invention, shut off from the cathode by a louvered or a slotted device. The protective apparatus may likewise be located with the same effect also at any desired other suitable point of the path of the current between the anode and the cathode.

An embodiment of this invention is illustrated in the accompanying drawings in

40 which:—

Figure 1 is an elevation in partial section of an embodiment of the invention, and

Fig. 2 is a plan of the louver shown in Fig. 1.

g is the metallic vacuum vessel; *a* is the anode and *k* is the mercury cathode; *o* is an insulator for the purpose of introducing the anode *a* in a gas-tight and insulated manner. This insulator is continued downward in the form of the metallic arc-guiding sleeve *h*, the lower opening of which is closed by the louver *i*. In its passage in the direction of the arrow *j*, the arc is caused by the walls of the louvered closure to make two bends in its path. The funnel-shaped arc-collector *l* serves chiefly for preventing a discharge between the anode and the wall of the vessel. Experience has shown that the improvement is highly suitable to render metal-vapor rectifiers for large outputs as well as for high voltages of several thousand volts, quite safe in their operation, and in particular it constitutes an effective agent against the so-called back ignitions.

The several inclined surfaces of the louver may be made of metal, for instance iron. The distance of the surfaces apart may be 1-2 cm. and it is not absolutely necessary that these surfaces should completely overlap one another in the direction of the axis of the anode. It is essential that the opening of the sleeve *h* should appear to be closed when viewed from the direction of the cathode. The louver devices do not constitute an appreciable obstacle and also they do not cause any increase in the total voltage drop of the arc.

What I claim is:—

A protective apparatus for metal-vapor rectifiers including an anode, a cathode, an arc guiding sleeve and a louvered protecting wall at the open mouth of said arc guiding sleeve, the planes of the louvers being approximately perpendicular to the connecting line between anode and cathode.

In testimony whereof I have signed my name to this specification.

Dr. BÉLA BENÖ SCHÄFER.
